United States Patent Office

Des. 227,367
Patented June 19, 1973

227,367

AIR HEATER

Hermann R. Schaefer, 375 Midland Ave.,
Bridgeport, Conn. 06605

Filed Dec. 9, 1971, Ser. No. 206,589

Term of patent 14 years

Int. Cl. D23—03

U.S. Cl. D23—122

Fig. 1.

Fig. 2.

Fig. 3.

Fig. 4.

Fig. 5.

Fig. 6.

Fig. 7

FIG. 1 is a front perspective view of an air heater showing my new design;

FIG. 2 is a rear perspective view of the air heater of FIG. 1;

FIG. 3 is a top plan view of the air heater of FIG. 1 on an enlarged scale;

FIG. 4 is a front elevation of the air heater of FIG. 1 on an enlarged scale;

FIG. 5 is a rear elevation of the air heater of FIG. 1 on an enlarged scale;

FIG. 6 is a bottom plan view of the air heater of FIG. 1 on an enlarged scale;

FIG. 7 is a side elevation of the air heater of FIG. 1 on an enlarged scale.

I claim:

The ornamental design for an air heater, as shown and described.
